UNITED STATES PATENT OFFICE.

WILLIAM P. HAMMOND, OF CHARLESTOWN, MASSACHUSETTS, ASSIGNOR TO UNITED SHOE MACHINERY COMPANY, OF PATERSON, NEW JERSEY, A CORPORATION OF NEW JERSEY.

SHOE-RACK.

1,100,072.

Specification of Letters Patent. Patented June 16, 1914.

Application filed July 21, 1913. Serial No. 780,146.

To all whom it may concern:

Be it known that I, WILLIAM P. HAMMOND, a citizen of the United States, and a resident of Charlestown, in the county of 5 Suffolk and Commonwealth of Massachusetts, have invented an Improvement in Shoe-Racks, of which the following description, in connection with the accompanying drawings, is a specification, like characters 10 on the drawings representing like parts.

This invention relates to shoe racks such as are used in shoe factories for conveying shoes from place to place in the course of their manufacture.

15 The character of the invention may be best understood by reference to the following description of an illustrative embodiment thereof shown in the accompanying drawings, wherein:

20 Figure 1 is a view partly in section and partly in side elevation of an illustrative shoe rack embodying the invention; Fig. 2 is an end elevation partly in section of the rack shown in Fig. 1; Fig. 3 is a side elevation of the rack shown in Fig. 1 in collapsed position; Fig. 4 is an end elevation of a modification; and Fig. 5 is a section taken on line 5—5 of Fig. 4.

25 Referring to the drawing, the illustrative rack shown herein as embodying the invention comprises a base frame 1 conveniently composed of longitudinally extending spaced angle bars 3—3 connected by flat cross bars 5. This base frame is mounted on appropriate casters 4 secured thereto. At each 30 end of the base frame is an upright frame 7 comprising angle bars 9, 9 bolted or otherwise connected at their upper ends by a horizontal tube 11 slotted to receive said angle bars. The upright angle bars 9 may be connected adjacent their lower ends by cross bars 13.

35 To support trays between the upright frame 7 each of the angle bars 9 is provided with brackets 15 spaced at appropriate intervals to correspond with the desired location of the trays. Supported on these brackets are usual trays 17 provided with partitions forming pockets for receiving the 40 shoes. It is sometimes desired to employ a rack for so many trays that uprights of sufficient length to receive them would each be longer than the base frame. In my copending application Serial No. 731,106, filed 45 Nov. 13, 1912, is shown a collapsible rack

in which the uprights may be folded down into superposed relation on the base frame. This would be impossible, however, if the upright frames were longer than the base frame. It is highly desirable to have the 60 rack capable of collapsing. To enable the rack shown herein to be collapsed the lower end of each of the upright angle bars 9 is pivotally connected to a base frame angle bar 3 by a bolt 19 entered through registering apertures in said upright angle bar and base frame bar and provided with a butterfly nut 21 (Fig. 2) to facilitate the operation thereof. To prevent inadvertent loosening of this bolt it may be provided 65 with a usual spring locking washer 23 not necessary to be shown in detail herein. Each upright angle bar is connected to a base angle bar by diagonal brace links 25.

70 When it is desired to collapse the frame 75 the bolts 19 are removed and the right hand upright frame 7 (Fig. 1) is rocked in a contra-clockwise direction down on to the base frame 1. In the course of this rocking movement the upright frame will be moved 80 by its brace links 25 so that the lower end thereof projects beyond the end of the base frame. The pivot bolts of the left hand upright frame are then removed and said frame is rocked down to overlie the right 85 hand frame, as shown in Fig. 3. In the course of this movement the lower end of said upright frame is moved in from its end of the base frame and along the other upright frame. The rack frames when thus 90 folded are in compact relation and occupy very little space, thereby enabling a large number of the racks to be stored away when not in use without taking up an objectionable amount of room. When it is desired to 95 set up the rack it is merely necessary to swing its end frames to their upright positions and replace the pivot bolts. These tall, upright end frames have more or less resilience, and in wheeling the racks from 100 place to place, are liable to be pulled away from the trays and permit the latter to drop from their brackets. To guard against this and stiffen the rack as a whole the horizontal tubes 11 at the tops of the end frames 105 may be connected by a tie rod 27 entered through apertures in said tubes and rendered adjustable by a nut 29 at one end thereof. By this construction after the trays have been introduced the tie rod can 110

be set up, thereby drawing the upright end frames toward one another, causing the same to grip one or all of the trays and thereby prevent dislocation of the trays and 5 very materially contribute to the stiffness of the rack structure as a whole.

The tie rod construction described is sufficient to prevent the end frames from spreading and dropping the trays, but to prevent 10 the trays from jumping up off of their brackets further securing means may be provided therefor. To this end one or more metal straps 31 may be provided each having its upper end detachably entered into a 15 slot in the under side of the upper horizontal bar 11, said end being arranged preferably to engage the inner surface of the opposite wall of said tube. The lower end may be bolted or otherwise secured to one of the 20 cross bars 13, referred to. Each of the trays may be secured to said straps by screws 33.

In Fig. 2 two straps are shown for each end frame, whereas in the modification shown in Fig. 5 but a single strap is shown. 25 These straps may have more or less flexion, which will permit them to bend and conform to any irregularity in vertical alinement of the end trays.

In the modification shown in Figs. 4 and 30 5 there is shown a tie rod 35 which instead of being directly connected to the horizontal tubes 11, as in Figs. 1 and 2, is connected directly to the straps 31 at a point to pass through and parallel rods 37 forming the 35 bottom of the top tray and in the plane of said rods. This is an extremely advantageous location for the tie rod since it is not exposed to danger of being bent or distorted, but on the contrary is fully protected by its 40 location within the tray. Furthermore, it eliminates the necessity of providing special devices for holding the tray to the strap since the stay is also effective for this purpose.

45 When it is desired to remove the trays from the rack the screws 33 connecting the trays to the straps 31 are first removed, then the strap at one end of the rack is removed from the rack by releasing the screw which 50 connects the same to the cross bars 13 and dropping the strap to permit its upper end to escape from the slot in the horizontal tube 11. The removal of the end strap permits the trays to be rocked on their longitudinal axes and projected slightly through 55 the end frame in one direction sufficiently to escape the angle bars of the opposite end frame, whereupon the trays may be readily adjusted in an opposite direction and re- 60 moved from the rack.

By my invention is provided a rack of simple organization which will stand hard usage without getting out of order and which may be readily knocked down into 65 collapsed form when desired.

Having described illustrative embodiments of the invention without limiting the same thereto, what I claim as new and desire to secure by Letters Patent is:

1. A foldable shoe rack comprising in 70 combination, a base frame; unitary uprights each longer than said base frame; means detachably securing the lower ends of said uprights to said base frame; brace links 75 pivotally connected to said base frame and uprights; shoe tray supporting elements distributed at intervals along said uprights, trays supported upon said elements and means for maintaining said uprights in erected position, in supporting relation to 80 said trays, said base frame, links and uprights having provision permitting the folding of the latter down toward said base frame in collapsed relation therewith.

2. A foldable shoe rack comprising in 85 combination, a base frame, upright bars arranged in pairs at each end of the base frame, transverse connecting means at the upper and lower portions of each pair of upright bars, bolt-like members detachably 90 securing the lower ends of said bars to said base frame, brace links pivotally connected to said base frame and bars, transverse shoe tray supporting elements distributed along 95 said bars, trays detachably supported upon said elements, and means for detachably holding said trays upon said elements, said bars being foldable onto the base frame upon removal of the bolt-like members.

3. A foldable shoe rack comprising in 100 combination, a base frame, upright bars each longer than said base frame, bolt-like members detachably securing the lower ends of said bars to said base frame, brace links 105 pivotally connected to said base frame and bars, transverse shoe tray supporting elements distributed along said bars, trays detachably supported upon said elements, and means coacting with the upper portions of the opposite end bars and extending longitudinally of the rack to spring said bars toward each other, said bars being foldable onto the base frame upon removal of the bolt-like members.

4. A shoe rack comprising in combination, 115 a base frame; upright end frames connected to said base frame; tray supporting brackets on said upright end frames; an upright strap connected to each end frame, and means detachably connecting said straps to 120 said trays to hold the latter on said brackets.

5. A foldable shoe rack comprising in 125 combination, a base frame, upright end bars having pivotal connection with and foldable onto the base frame, brace links connected to said base frame and bars, transverse shoe tray-supporting elements distributed along 130 said bars, trays detachably supported upon said elements, and means distinct from said trays and coacting with the upper portions

of the opposite end bars and extending longitudinally of the rack to spring said bars toward each other thereby to maintain said side trays and their supporting elements in folded or collapsed relation.

8. A foldable shoe rack comprising in combination a base frame, upright bars each longer than said base frame, means detachably securing the lower ends of said bars to said base frame, brace links pivotally connected to said base frame and bars, transverse shoe tray supporting elements distributed along said bars, trays detachably supported upon said elements, and upright bars detachably connected to the said trays and to the bars, to hold said trays in position, said bars being foldable down toward the base frame in collapsed relation therewith.

9. A foldable shoe rack comprising in combination a base frame, upright bars each longer than said base frame, means detachably securing the lower ends of said bars to said base frame, brace links pivotally connected to said base frame and bars, transverse shoe tray supporting elements distributed along said bars, trays detachably supported upon said elements, upright strips detachably connected to the said trays and to the bars, to hold said trays in position, and means connected to said strips for receiving the upper ends of said trays, said bars being foldable down toward the base frame in collapsed relation therewith.

10. A foldable shoe rack comprising in combination a base frame, upright bars

each longer than said base frame, bolt-like members detachably securing the lower ends of said bars to said base frame, brace links pivotally connected to said base frame and bars, transverse shoe tray supporting elements distributed along said bars, trays detachably supported upon said elements, means for detachably holding said trays upon said elements, and a longitudinally arranged tie-rod passing through and engaging said means for detachably holding the trays, to draw the opposing bars toward each other, thereby to grip the trays, said bars being foldable onto the base frame upon removal of said bolt-like members.

9. A foldable shoe rack comprising in combination, a base-frame, unitary uprights each longer than said base frame, means detachably securing the lower ends of said uprights to said base frame, brace links pivotally connected to said base frame and uprights, shoe tray supporting elements distributed at intervals along said uprights, trays supported upon said elements, and an adjustable tie-rod secured to said uprights and having provision for drawing the latter toward the shelves interposed between them, said bars being foldable onto the base frame upon removal of said detachable securing means.

In testimony whereof, I have signed my name to this specification, in the presence of two subscribing witnesses.

WILLIAM P. HAMMOND.
